L. J. LE MESURIER,
AIRPLANE LAUNCHING APPARATUS,
APPLICATION FILED MAY 6, 1920.

1,388,361.

Patented Aug. 23, 1921.

UNITED STATES PATENT OFFICE.

LOUIS JOHN LE MESURIER, OF NEWCASTLE-UPON-TYNE, ENGLAND, ASSIGNOR OF ONE-HALF TO SIR W. G. ARMSTRONG, WHITWORTH & COMPANY, LIMITED, OF NEWCASTLE-UPON-TYNE, ENGLAND.

AIRPLANE-LAUNCHING APPARATUS.

1,388,361.

Specification of Letters Patent. Patented Aug. 23, 1921.

Application filed May 6, 1920. Serial No. 379,354.

To all whom it may concern:

Be it known that I, LOUIS JOHN LE MESURIER, subject of the King of England, and residing at Newcastle-upon-Tyne, 5 Northumberland, England, have invented certain new and useful Improvements in Airplane-Launching Apparatus, of which the following is a specification.

This invention relates to apparatus for launching aeroplanes from the decks of barges, ships or like restricted spaces and has for its object to provide an apparatus of simple construction which will obviate the employment of the airtight glands through 15 which it has hitherto been necessary to pass some of the wire ropes.

According to this invention a carriage for the aeroplane is mounted to travel on a track formed on the deck or like structure 20 and a cylinder actuated by the expansion of compressed air is mounted to travel on a second track, parallel to the first track, the carriage being connected by means of a rope to the cylinder in such a way that movement 25 of the latter causes acceleration of the carriage along its track. The carriage is also connected to the cylinder by a second rope in such a manner that a retardation of the carriage takes place after the aeroplane has 30 been released therefrom, ports being so formed in the piston that during the final portion of the cylinder's travel air is compressed therein. The carriage is retained in its initial position by means of a catch or 35 trigger, and the air is then introduced into the cylinder so that the carriage is drawn forward along its track directly the trigger is released without any valve gear or the like being necessary. A cam or ramp suitably 40 placed on the track or some other part of the main structure automatically releases the aeroplane from its carriage when the maximum speed has been attained.

One form of apparatus according to this 45 invention is illustrated by way of example in the accompanying drawings, in which,

Figure 1 is a side elevation.

Fig. 2 is a plan on an enlarged scale, partly 50 in section, showing the compressed air cylinder and its ram, and

Fig. 3 is a diagram drawn to a larger scale than Fig. 1 showing a trip mechanism omitted from that figure.

The aeroplane A is placed upon a carriage B which is mounted to travel upon a track 55 or rails B' extending the full length of the deck or other main structure. Formed parallel to and preferably below the main track B' is a second set of rails C, along which a cylinder D, having wheels D', is adapted to 60 travel relatively to a fixed ram E under the expansion of a charge of compressed air. The carriage B is connected to the cylinder D by a wire rope F whose ends F' F² are 65 respectively secured to the fore part of the carriage and a fixed portion G of the structure, the rope being passed around a pulley H on the fore end of the cylinder in such a way that an acceleration twice that of the cylinder is imparted to the carriage B. A 70 retarding rope J is similarly provided and secured to the carriage and structure but so arranged as to oppose the motion of the accelerating rope F, the ends of the retarding rope being respectively secured to a fixed portion K of the structure and to the carriage B and passing over a pulley L on the cylinder.

A trip mechanism, not shown in Figs. 1 75 and 2 but illustrated diagrammatically and on a larger scale in Fig. 3 is fitted to the traveling carriage B actuated by a cam or ramp B² suitably placed near the track B' so that the aeroplane is automatically released after it has attained its maximum speed. Such trip mechanism is unnecessary 80 when the apparatus is used for launching a seaplane.

The trip mechanism shown in Fig. 3 comprises a lever O pivoted at its lower end to the carriage B and having its upper end adapted to engage the axle A' of the aeroplane. This lever O is provided with a safety catch P which holds the axle in place 85 and prevents the aeroplane from creeping or lifting until the maximum speed is attained. Until then the safety catch is held in place by a pivoted pawl R held by a spring S against a stop T, but when the maximum speed is reached the lower end of the pawl R is brought into contact with a ramp B² fixed adjacent to the track clear of the carriage. This turns the pawl against the action of its spring S and releases the safety catch P.

The carriage B is normally retained in the launching position by means of a suitable 105

catch or lever M secured to the rear end of the main structure G.

- The traveling cylinder D is adapted to reciprocate relatively to a stationary ram E 5 having a hollow shank or rod E' provided near its forward end with suitable exhaust ports E² which are uncovered after the cylinder has moved forward a predetermined distance sufficient to impart the necessary 10 launching acceleration to the carriage. For the remainder of its travel the air trapped between the rear end of the cylinder and inner face of the piston E³ is compressed, so retarding the final portion of the cylinder's travel, while the charge of compressed air hitherto operating between the face of the piston and closed forward end of the cylinder, escapes freely through the open exhaust ports E² into the atmosphere.
- 20 When the aeroplane is to be launched the carriage is anchored to the rear of the track or structure by the retaining lever M and the cylinder D is charged to the required pressure with compressed air through the 25 charging valve N which is then closed. The retaining lever M is then released, whereupon the cylinder D will be driven forward owing to the expansion therein of the compressed air and the carriage B will receive 30 twice the amount of acceleration through the acceleration rope F.

As the device is self-contained as regards power after being charged with compressed air there will be no losses due to wire drawing at valves during the acceleration.

When the cylinder has reached its maximum speed the trip mechanism releases the aeroplane from the carriage and the exhaust ports E² in the hollow shank of the ram E 40 are simultaneously uncovered, so that the main charge of compressed air escapes into the atmosphere while the air trapped between the rear end of the cylinder and inner face of the piston E³ is compressed, thus 45 acting as a retarding buffer. If desired an auxiliary buffer spring may be provided to assist in bringing the empty carriage to rest.

To prepare the device for a further 50 launch the carriage is rolled back to the starting position and held there by the retaining lever M while the cylinder is recharged with compressed air.

Although in the above description single 55 acceleration and retarding ropes have been referred to, in practice these may be duplicated and provided on each side of the cylinder, the latter having pulleys on either side for this purpose.

60 It will be understood that other suitable means for holding and releasing the traveling cylinder and carriage may be used; as, for example, a release mechanism acting directly upon the cylinder without departing 65 from this invention.

In the following claims the term air plane is intended to cover not only an aeroplane as illustrated in the drawings but also a seaplane or a similar flying machine not provided with wheels.

What I claim as my invention and desire to secure by Letters Patent is:—

- 70 1. In apparatus for launching an air plane from a restricted area the combination of a track, a carriage adapted to travel thereon, a second track parallel to the first track, a movable member adapted to travel on the second track, and means operatively connecting said track, movable member, and carriage whereby acceleration is imparted 75 to the carriage at the beginning of the movement of said member and retardation is imparted thereto as said member reaches the end of its travel.
- 80 2. In apparatus for launching an air plane from a restricted area the combination of a track, a carriage adapted to travel thereon, a second track parallel to the first track, a movable member adapted to travel on the second track, a pulley on said member, an accelerating rope, a second pulley on the movable member and a retarding rope passing around said pulley having its ends 85 respectively secured to the carriage and to a fixed part of the track structure.

90 3. In apparatus for launching an air plane from a restricted area the combination of a track, a carriage adapted to travel thereon, a second track parallel to the first track, a member adapted to travel on the second track under the expansion of a fluid pressure medium and flexible connections 95 between the carriage, movable member, and track whereby acceleration is imparted to the carriage at the beginning of the movement of said member, and retardation as 100 said member approaches the limit of its movement.

105 4. In apparatus for launching an air plane from a restricted area the combination of a track, a carriage adapted to travel thereon, a second track parallel to the first track, a member adapted to travel on the second track under the expansion of a fluid pressure medium, a flexible connection 110 between the carriage and movable member whereby acceleration is imparted to the carriage, and flexible connections between said 115 movable member and carriage whereby the carriage is accelerated during the greater portion of its travel and retarded at the end of its movement.

120 5. In apparatus for launching an air plane from a restricted area the combination of a track, a carriage adapted to travel thereon, a second track below the first track and parallel thereto, a fixed plunger, a cylinder adapted to move on the second track under the 125 expansion of a fluid pressure medium relatively to the fixed plunger, a pulley on the 130

cylinder, and an accelerating rope having its ends secured to the carriage and to a fixed part of the track structure passing around said pulley.

retarding rope passing around the second pulley having its ends respectively secured to the rear end of the carriage and to the forward portion of the track structure.

5 6. In apparatus for launching an air plane from a restricted area the combination of a track, a carriage adapted to travel thereon, a second track below the first track and parallel thereto, a fixed plunger, a cylinder adapted to move on the second track under the expansion of a fluid pressure medium relatively to the fixed plunger, a pulley on the cylinder, an accelerating rope having its ends secured to the carriage and to a fixed 10 part of the track structure passing around said pulley, a second pulley on the cylinder and a retarding rope having its ends secured to the carriage and a fixed part of the track structure passing around the second pulley.

15 7. In apparatus for launching an air plane from a restricted area the combination of a track, a carriage adapted to travel thereon, a second track below the first track and parallel thereto, a fixed plunger, a cylinder adapted to move on the second track under the expansion of a fluid pressure medium relatively to the fixed plunger, a pulley on the cylinder, an accelerating rope having its ends secured to the carriage and to a fixed 20 part of the track structure passing around said pulley, a second pulley on the cylinder and a retarding rope having its ends secured to the carriage and a fixed part of the track structure passing around the second pulley.

25 8. In apparatus for launching an air plane from a restricted area the combination of a track, a carriage adapted to travel thereon, a second track below the first track and parallel thereto, a fixed plunger, a cylinder adapted to move on the second track under the expansion of a fluid pressure medium relatively to the fixed plunger, a pulley on the cylinder, an accelerating rope having its ends secured to the carriage and to a fixed 30 part of the track structure passing around said pulley, a second pulley on the cylinder, a retarding rope having its ends secured to the carriage and a fixed part of the track structure passing around the second pulley, 35 and means for retarding the cylinder toward the end of its forward stroke.

9. In apparatus for launching an air plane from a restricted area the combination of a track, a carriage adapted to travel thereon, a second track below the first track and parallel thereto, a fixed plunger, a cylinder adapted to move on the second track under the expansion of a fluid pressure medium relatively to the fixed plunger, a pulley on the cylinder, an accelerating rope having its ends secured to the carriage and to a fixed part of the track structure passing around the second pulley, and means for retarding the cylinder toward the end of its forward stroke.

9. In apparatus for launching an air plane 55
from a restricted area the combination of a
track, a carriage adapted to travel thereon,
a second track mounted below the first track
and parallel thereto, a fixed plunger, a cyl-
inder adapted to move on the second track 60
under the expansion of a fluid pressure me-
dium relatively to the fixed plunger, a pulley
on the forward end of the cylinder, an acceler-
ating rope passing around said pulley
having its ends respectively secured to the 65
forward portion of the carriage and to the
rear end of the track structure, a second pul-
ley near the rear end of the cylinder, a re-
tarding rope passing around the second pul-
ley having its ends respectively secured to 70
the rear end of the carriage and to the for-
ward portion of the track structure, and
means for retarding the cylinder toward the
end of its forward stroke.

25. adapted to move on the second track under the expansion of a fluid pressure medium relatively to the fixed plunger, a pulley on the cylinder, an accelerating rope having its ends secured to the carriage and to a fixed
 30 part of the track structure passing around said pulley, a second pulley on the cylinder, a retarding rope having its ends secured to the carriage and a fixed part of the track structure passing around the second pulley,
 35 and means for retarding the cylinder toward the end of its forward stroke.

10. In apparatus for launching an air plane from a restricted area the combination of a track, a carriage adapted to travel thereon, a second track mounted below the first track and parallel thereto, a fixed plunger, a hollow stem therefor having exhaust ports therein, a cylinder adapted to move under the expansion of a fluid pressure medium relatively to the fixed plunger upon the second track, a pulley mounted on the forward end of the cylinder, an accelerating rope passing around the pulley having its ends respectively secured to the forward end of the carriage and to the rear end of the track structure, a second pulley on the cylinder, a retarding rope passing around the second pulley having its ends respectively secured to the rear end of the carriage and the forward end of the track structure and means for retarding the forward movement of the cylinder directly the latter has uncovered the exhaust ports in the plunger stem 75 80 85 90 95

8. In apparatus for launching an air plane from a restricted area the combination of a track, a carriage adapted to travel thereon, a second track mounted below the first track and parallel thereto, a fixed plunger, a cylinder adapted to move on the second track under the expansion of a fluid pressure medium relatively to the fixed plunger, a pulley on the forward end of the cylinder, an accelerating rope passing around said pulley having its ends respectively secured to the forward portion of the carriage and to the rear end of the track structure, a second pulley near the rear end of the cylinder and a

In testimony whereof I have signed my name to this specification.

LOUIS JOHN LE MESURIER.
